UNITED STATES PATENT OFFICE.

FREDERICK T. SNYDER, OF OAK PARK, ILLINOIS.

ELECTRIC-FURNACE CONTACT.

1,271,093.

Specification of Letters Patent.

Patented July 2, 1918.

Application filed March 1, 1917. Serial No. 151,718.

To all whom it may concern:

Be it known that I, FREDERICK T. SNYDER, a citizen of the United States, residing at Oak Park, in the county of Cook and State 5 of Illinois, have invented a certain new and useful Improvement in Electric-Furnace Contacts, of which the following is a full, clear, concise, and exact description.

The present invention relates to improvements in electric furnaces and more particularly to electric furnace contacts.

As heretofore constructed, electric furnace contacts have been provided with an elongated solid cylindrical portion adapted 15 to extend through the bottom of the furnace and into the melting chamber thereof, the lower end of said contact being enlarged and provided with a cooling chamber terminating below the shell of said furnace. As 20 is well known in the art, a small amount of molten metal remains in the melting chamber of the furnace after the pouring operation. This metal, when it hardens, becomes an integral part of the contact forming what is commonly termed a "mushroom" on the inner end thereof. This formation renders difficult the removal of the contact from the furnace in a downward direction, while the enlargement on the lower 25 end of the contact within which is formed the cooling chamber, prevents the removal of the contact from the furnace in an upward direction. Furthermore, in the use of contacts as now constructed, molten metal 30 sometimes leaks out through the bottom of the furnace around the contact during the melting operation, owing to the inability of the cooling chamber, which terminates below the bottom of said furnace, to cool 35 the metal enough as it nears the lower end of said contact, to cause the same to congeal and thus close any opening which has been formed between the said contact and the adjacent walls of the opening in which 40 it is mounted. Another disadvantage in the use of this former form of contact, resides in what may be termed "piping" of the contact when it is made of a casting, or in other words, in the formation of a small 45 opening through the contact from the cooling chamber thereof to the melting chamber of the furnace, due to shrinkage of the casting. This casting shrinkage pipe does 50 not extend entirely through the contact when

cast, but is sometimes opened up by the 55 partial melting down of the upper end of said contact when in use in the furnace. This "pipe" or passage thus formed, may permit water to pass from the cooling chamber into the molten metal, where the water 60 is decomposed by the intense heat and the nascent oxygen thus liberated, oxidizes the metal and thereby modifies unfavorably its physical characteristics. A further objection to the use of contacts, as now commonly constructed, resides in the excess heat conductivity which they afford by reason of their large cross-sectional area. It is well known, that the passage of an electric current through a conductor produces rings 65 of magnetic force, not only around the outside of the conductor, but also within the same, the rings of magnetic force being formed within said conductor around each 70 thread of current passing therethrough. 75 Where the current rapidly alternates in direction, these rings of magnetic force move in and out and reacting with the threads of electric current cause the threads of current to be forced outward from the center 80 axis of the conductor, toward the outer surface thereof. In other words, most of the current, when alternating flows through the conductor adjacent to the outer surface 85 thereof, little current flowing through the central area. This is commonly termed the electric "skin effect" and is more marked in conductors made of magnetic material, such as steel. It will be seen therefore, that 90 the central portion of the contact conducts very little current, while on the other hand, it acts to increase the objectionable conductivity of heat from the furnace.

The present invention therefore aims to 95 overcome these various disadvantages, and has for one of its objects, the provision of a contact which shall be provided with means whereby a maximum electrical conductivity with a minimum heat conductivity is obtained, said contact being so 100 constructed as to permit of the same being withdrawn from the furnace quickly and with comparative ease, thereby obviating the objections above noted.

Another object of the present invention 105 resides in the provision of a contact of the type described, which shall be provided with an improved cooling chamber, adapted to

extend into the shell of the furnace to thereby prevent the leakage of molten metal through the bottom of said furnace around said contact.

Other objects and advantages will be apparent from the following description, taken in connection with the accompanying drawings, wherein the preferred embodiment of the invention is illustrated.

10 Figure 1 is a transverse sectional view taken through an electric furnace showing the contact in position.

Fig. 2 is an enlarged vertical sectional view of the contact.

15 Fig. 3 is a cross sectional view of the contact taken on the line 3—3 of Fig. 2.

Fig. 4 is a section taken on the line 4—4 of Fig. 1.

20 Fig. 5 is a section taken on the line 5—5 of Fig. 2.

Referring more in detail to the drawings, the electric furnace is shown at 1 and is provided with the usual refractory lining 2, a heat insulating lining 3 and an outer 25 metallic shell 4. The melting chamber of the furnace is indicated at 5. Extending through the bottom of the furnace and terminating in the melting chamber 5 thereof, is provided an opening 6, which is adapted to receive the electric contact 7.

The contact 7 is shown in the drawings as provided at its lower end with a suitable cooling dome 8, and a plurality of thin flat conducting ribs 9, extending up from said dome 8. These flat conducting ribs 9 are spaced apart and terminate at their inner ends at a point short of the central axis of the contact 7, as shown in Fig. 3. The upper inner edges of the conducting ribs 9 merge into a substantially tubular extension 10, said extension being shown projecting beyond the upper ends of the conducting ribs 9, into the melting chamber 5 of the furnace 1. This is to facilitate the initial formation of the 45 arc between the contact 7 and the electrode (not shown), when first starting with a new contact. Shortly after the melting operation has been started, however, this projecting portion of the tube 10 melts off flush 50 with the upper ends of said conducting ribs 9. It will be noted from this construction that the contact 7 is provided with a central opening extending from the upper surface of the cooling dome 8, up through the 55 entire length of said contact, thereby eliminating the possibility of an excessive heat conductivity, and at the same time providing means whereby a maximum electrical conductivity is obtained. The inner wall of 60 the cooling dome 8 is preferably provided with a plurality of heat radiating fins 11. The structure thus far described is preferably cast integral, and of the same material that is being melted within the furnace.

A suitable hollow plug 12, which may be of cast iron, is shown extending upwardly into the cooling dome 8 and is so positioned with relation thereto as to form a chamber 13, the plug 12 being provided at its lower 70 end with a screw-threaded portion 14, which is adapted to engage the lower end of the contact 7, to thereby retain said plug in position. A suitable cooling medium such as water, is circulated through the chamber 13, 75 the same being forced into said chamber through the intake pipe 15 and out through the outlet pipe 16. It will be noted that the outlet pipe leaves the cooling chamber 13 at substantially the uppermost portion thereof. This construction acts to effectively remove any air which may be trapped in the chamber 13, and also removes the hottest water first, as it rises within the same. It will be noted that the plug 12 is of substantial size and extends into the cooling dome 8 in such manner that the walls thereof lie in close proximity to the inner wall and radiating fins 11 of the dome 8. This permits of an increased velocity in the water circulation through the chamber 13, by reducing the cross section of the water flow, which increases the heat transfer capacity of the water jacket contact area. 80 85 90 95

It will be noted from Fig. 1 of the drawings, that the cooling chamber 13 of the contact extends past the outer metallic shell 4 of the furnace and into the refractory lining 2 thereof. This structure provides means whereby that portion of the contact adjacent said cooling chamber and within the shell of the furnace is effectively cooled during the melting operation. The cooling chamber also acts to cool that portion of the refractory lining 2 of the furnace which lies adjacent thereto. From this it will be noted that should any of the molten metal from the chamber 5 leak down around the contact 7, the same will be congealed around said contact when it reaches the lower portion thereof, by the action of the cooling medium thereon. The metal thus congealed, will act as a barrier and prevent any further leakage. This cooling can be conveniently accomplished by extending the bottom of the 100 furnace downwardly in the shape of a cone, the contact being inserted in the tip of the cone. Heretofore, electric steel furnaces of this type have been built with a flat bottom through which the contacts projected. 105 110 115 120

It will be noted from the construction of the contact as hereinbefore set forth, that the same is of substantially the same diameter throughout. This permits of the contact being drawn upward through the melting chamber 5, when it is desired to remove the same, for the purpose of replacing it with a new one. It will be noted that in the formation of the contact as herein described, no "piping" can take place, by reason of the 125 130

fact that the conducting ribs 9 are so thin as to prevent the formation of openings therein. It will thus be seen that the possibility of oxidation of the metal, heretofore caused by the "piping" of the contact, has been eliminated, as no large masses of castings are permitted by the present design of contact within which casting "pipes" can form.

The current is conducted to the contact 7 by means of a suitable strap 17, which is clamped about the lower end of the contact, by means of the bolts 18. A support 19 cooperates with the bolts 18 to hold the strap 15 in place. The flexible conductors 20 are preferably clamped between the ends of the strap 17 as shown, and are supported by means of a suitable supporting member 21. A plate 22, preferably asbestos board, is 20 shown mounted over the strap 17 and the conductors 20 to protect the same against injury from molten metal, which may drop from the furnace.

It is obvious that various changes and 25 modifications may be made in the structure herein illustrated, and the right is therefore reserved to make such changes and modifications as may fall within the scope of the appended claims.

Having thus described my invention, what 30 I claim as new and desire to secure by Letters Patent of the United States is:

1. A contact for electric furnaces, comprising a member having a small cross sectional area in proportion to its cross sectional perimeter, whereby said contact has high conductivity for alternating electric current and a low conductivity for heat.

2. A contact of the type described, comprising a cooling dome, a plurality of spaced-apart conducting ribs, and a tubular extension adapted to project into the melting chamber of a furnace.

3. A contact for electric furnaces, comprising a tube having conducting ribs mounted thereon.

4. A contact for electric furnaces, comprising a tube having radial ribs mounted thereon, capable of conducting both electricity and heat.

5. A contact for electric furnaces, comprising a hollow portion adapted to contain a cooling medium and ribs mounted thereon, capable of conducting both electricity and heat.

6. A contact for electric furnaces, comprising a hollow portion adapted to contain a cooling medium and ribs projecting therefrom inside and outside said hollow portion.

7. The combination with an electric furnace, containing a molten bath, of a contact containing a cooling medium and a thin metallic conductor between the bath and the cooled portion of the contact.

8. The combination with an electric fur-

nace, containing a molten bath, of a cooling chamber and a thin metal conductor carrying heat and electricity between the bath and the cooling chamber.

9. The combination with an electric furnace, containing a molten bath of a cooling chamber and a thin metal conductor in electrical and thermal contact with both bath and chamber. 70

10. A contact for electric furnaces comprising a plurality of spaced-apart radially arranged conducting ribs, the inner edges of said ribs terminating short of the longitudinal axis of said contact. 75

11. A contact for electric furnaces comprising a plurality of vertical spaced-apart conducting ribs, said ribs merging into an extension at the upper end of said contact. 80

12. A contact for electric furnaces, containing hot material, comprising a cooling chamber provided with an inlet and an outlet for a cooling medium, a conductor having a small horizontal cross section adapted to transfer electricity and little heat from such hot material to said chamber, said outlet being arranged to remove the cooling medium from that portion of the chamber nearest to said conductor. 90

13. A contact for electric furnaces, containing hot material, comprising a cooling chamber below such material, a conductor having a small cross sectional area in proportion to its cross sectional perimeter arranged between said material and said chamber, and an outlet arranged to remove the cooling medium and any liberated gas 100 from the top of said chamber. 95

14. A contact for electric furnaces, comprising a cooling dome, a plurality of spaced-apart conducting ribs cast integral therewith and extending upwardly therefrom and merging into an extension, the inner wall of said cooling dome being provided with a plurality of heat radiating fins. 105

15. A contact for electric furnaces, comprising a cooling dome, a plurality of spaced-apart conducting ribs cast integral therewith and extending upwardly therefrom and merging into an extension, the inner wall of said cooling dome being provided with a plurality of heat radiating fins, said cooling dome being adapted to receive a hollow plug, said plug co-operating with said dome to form a cooling chamber and means whereby water may be circulated 115 therethrough. 120

16. The combination with an electric furnace, of a contact therefor, comprising a cooling chamber and a filler substantially filling the space in said cooling chamber, 125 whereby the amount of cooling medium within said chamber is reduced and the velocity of flow of said medium is increased.

17. The combination with an electric furnace, of a contact therefor, adapted to ex- 130

- 21
- tend through the bottom thereof, a conductor electrically connected therewith, and a shield adapted to divert from said conductor material leaving the furnace near said contact.
- 5 18. The combination with an electric furnace, of a contact therefor adapted to extend through the bottom thereof, one end of said contact extending below said bottom,
- 10 a strap adapted to encircle said end, a support for said strap, and means for clamping the ends of conductors between the ends of said strap, thereby affording means for the conduction of current to said contact, and
- 15 means for protecting said strap and said conductors against injury.
19. A contact of the type described, comprising a cooling dome cast integral therewith, a hollow plug adapted to be secured within said dome, and means for circulating a cooling medium between said dome and said plug.
20. The combination with an electric furnace of a contact adapted to extend through
- the bottom thereof, the ends of said contact 25 extending both above and below said bottom, one of said ends being of less diameter than the body of the contact.
21. The combination with an electric furnace, having a bottom in the form of a cone, 30 of a contact adapted to extend through the axis of said cone, and means for connecting said cone electrically with said contact.
22. The combination with an electric furnace, having a lower metal shell in the form 35 of a cone, of a metal contact entering the furnace through the point of said cone and refractory lining material filling the space between said cone and said contact.
23. The combination with an electric 40 furnace, of a bottom contact therefor, said contact comprising a plurality of spaced apart conducting ribs mounted within the refractory wall of the furnace.
- In witness whereof I hereunto subscribe 45 my name this 23rd day of February, A. D. 1917.
- FREDERICK T. SNYDER.
